CLAIM

The ornamental design for a luggage wrap, as shown and described.

DESCRIPTION

FIG. 1 is a rear perspective view of the luggage wrap showing my new design;

FIG. 2 is a rear elevation view thereof;

FIG. 3 is a front elevation view thereof;

FIG. 4 is a left side elevation view thereof, the right-side elevation view being a mirror image thereof;

FIG. 5 is a top plan view thereof;

FIG. 6 is a bottom plan view thereof; and,

FIG. 7 is a rear perspective view of the luggage wrap shown in use applied to an article of luggage.

The dash-dash broken lines showing stitching depict portions of the luggage wrap that form no part of the claimed design.

The dash dot dash lines in the drawings illustrate environment that forms no part of the claim.

1 Claim, 6 Drawing Sheets
